UNITED STATES PATENT OFFICE

CHARLES A. BUNKER, OF KANSAS CITY, MISSOURI, ASSIGNOR TO BUNKER-CLANCEY MANUFACTURING COMPANY, OF KANSAS CITY, MISSOURI, A CORPORATION OF MISSOURI

SMOKING STAND

Application filed August 1, 1927. Serial No. 209,813.

This invention relates to smoking stands of that general class in which the head, without a change in the location of the base, can be readily brought within convenient individual reach of several smokers grouped around the stand. Heretofore all such devices of which I have knowledge, have been provided with a heavy convex-faced base which rocks on the floor under the application 5 of pressure or force applied laterally to the head or top, and susceptible, when the stand is released after such tilting or rocking action, of rocking back to restore the stand as a whole to normal or upright position. Such 10 stands are relatively expensive and undesirably heavy, especially for home and office use, and a stand possessing the same function and advantages but lighter and less costly is a desideratum.

Accordingly, I have produced a stand comprising a flat-bottomed base, a stem rockingly related thereto and a weight to serve 15 as a pendulum for the stem and concealed within the base, as essential elements. The device also preferably includes a spring to 20 cooperate with the pendulum or weight in restoring the stem to upright position, the spring not only permitting the use of a weight of smaller size than would otherwise 25 be necessary, but tending to resist excessive tilting action of the stem and bring the same to a state of rest more quickly than such result could be obtained by the use of a weight alone.

With the object in view of producing an attractive, efficient and inexpensive smoking stand of the character outlined, the invention consists in certain novel and useful features of construction and combinations of parts as hereinafter described and claimed; and in order that it may be fully understood, reference is to be had to the accompanying drawing, in which:

Figure 1 is a view partly in side elevation and partly in central vertical section of a smoking stand embodying the invention.

Figure 2 is a top plan view of the same.

Figure 3 is a section on the line III—III 50 of Figure 1.

Figure 4 is a section on the line IV—IV of Figure 1.

In the said drawing, the base of the stand is of generally truncated cone form, and comprises a flat-bottomed pan 1 and a cover 2, 55 the upper margin of the wall of the pan being formed with an upstanding edge 3, which is formed with a seam to provide a stiff and smooth-finished edge. The bottom of the cover terminates in a depending and slightly 60 flaring flange 4 externally clasping the edge 3 of the pan. The engaging edge and flange are resilient and provide for frictional engagement which guards against accidental dislocation of the bottom from the cover 65 when the stand is lifted to move it from one place to another. The frictional grip, however, readily yields to properly applied force, so that the pan may be removed for emptying 70 purposes, as it is adapted to serve for the collection of ashes, burnt matches and the like, it being further understood that the connection is air-tight so that burning cigar or cigarette stubs shall become quickly extinguished to avoid contamination of the air 75 of the room in which the stand is located.

To further increase the stiffness of both the pan and cover and also to give both an attractive appearance, they are of fluted or beaded form in cross section. The cover is 80 in the form of a tapered ring and adjacent the upper or smaller end 5, is formed with an upwardly-facing external channel 6, and a surrounding downwardly-facing internal channel 7, for purposes which hereinafter 85 appear.

The stem comprises a lower tube member 8, which extends loosely into the base through the upper end of the cover, and terminates in about the plane of the lower edge of the latter. Above the cover, it is formed with a horizontal bead 9 and at its lower extremity is flared outwardly all around or at two or more points as at 10. A weight 11 of approximately mound-shape, fits slidingly on 95 the stem within the base and rests upon the flared portion 10 of the stem, the flare being produced upon the latter after the weight is applied thereto. A coil spring 12 loosely surrounds the stem and fits at its upper end 100

in the channel 7, and at its lower end bears upon the weight, the spring cooperating with the weight in holding the stem in and bringing it to a vertical position, and also serving as a cushion to prevent the weight sliding against the cover and producing an undesirable sound should the stand be lifted. The upper or main portion of the stem is in the form of a tube 13, fitting at its lower end upon the upper end of the stem member 8 and secured permanently thereto by the provision of a bead 14 tightly receiving the bead 9 of member 8. The lower end of the tube 13 is diametrically enlarged so as to provide a skirt portion 15 which depends into the channel 6 in such a manner that the stem as a whole can be rocked on the base without said skirt coming in contact with the side walls of channel 6 and producing an undesirable clatter or noise, the spring cushioning such rocking action regardless of its direction and serving to take up all play so that the action shall be noiseless.

The head 16 of the stand is of approximately funnel shape and terminates in a depending stem 17, fitting in the upper end of the main portion of the stem, the latter and the stem of the head being secured permanently together by the formation thereon of interlocking beads 18 and 19. The upper or mouth end of the funnel portion of the head is formed with a surrounding ledge or flange 20 preferably horizontal at its upper side, and terminating in a marginal bead 21 for stiffening and ornamental purposes, the flattened face of the ledge being provided with a plurality of radial depressions or channels 22 in which cigars or cigarettes may be held against ready dislodgment, and secured to the ledge in any suitable manner is a match box holder 23, which may be of conventional or any preferred form and hence is not described or shown in detail.

By reference to Figure 1 it will be seen that ashes, burnt matches, cigar and cigarette stubs deposited in the funnel shaped head will immediately drop therefrom through the stem and into the pan 1 of the base, thus insuring that ashes, matches and the like shall not be free to blow about the room or soil or burn a finished floor or rug or the like.

This device is preferably made of sheet steel for strength and rigidity and may be attractively finished in any color or combination of colors to match the decoration or finish of a smoking car or room. The stem and cap rock in any direction, and the stand as a whole cannot be readily tipped over, it being noted however that should this occur its contents would be retained in the pan and not spilled upon the floor, and when it is necessary to clean the pan, the pressure of the hand or foot against the pan and an upward jerk or pull upon the stem will detach the cover and other parts from the pan,

it being noted in this connection that the bottom of the cover is as low or lower than the bottom of the stem and hence the stem may be supported upright on the floor by the cover when the pan is being emptied.

From the above description, it will be apparent that this smoking stand possesses all of the advantages of the conventional smoking stand of the tilting class adverted to in the introductory part of this description, and possesses the additional advantages set forth in the statement of the objects of the invention, and while I have illustrated and described the preferred embodiment, it is to be understood that it is susceptible of modification in various particulars without departing from the principle of construction and mode of operation involved or from the spirit and scope of the appended claims.

I claim:

1. A smoking stand comprising a hollow base, a tubular stem resting on and extending upwardly from the base and bearing a rocking relation thereto, and communicating at its lower end with the chamber of the base, a receptacle carried by and communicating with the upper end of the stem, and means tending to normally hold the stem in upright position and return the same to such position after it is rocked without affecting the position of the base, the said base comprising an upper portion affording support to said stem, and a lower portion constituting a pan to underlie and receive waste material from said stem and removably connected to said upper portion.

2. A smoking stand comprising a hollow base, a stem resting on and extending upwardly from the base and bearing a rocking relation thereto, a receptacle carried by the stem, a weight or pendulum for the stem within the base and below the rocking point thereof, and a spring interposed between the weight and the overlying part of the base and exerting downward pressure upon the former.

3. A smoking stand comprising a hollow base, a stem extending down into the base and provided with a skirt portion resting on the base, a receptacle carried by the stem, and a weight mounted on the stem within the base to impose its weight and that of the stem and receptacle upon the base and through gravitational force restore the stem to upright position after the same has been tilted with the skirt serving as the fulcrum for such tilting movement.

4. A smoking stand comprising a hollow base, a stem extending down into the base and provided with a skirt portion resting on the base, a receptacle carried by the stem, a weight mounted on the stem within the base to impose its weight and that of the stem and receptacle upon the base and through gravitational force restore the stem to upright position after the same has been tilted with the

skirt serving as the fulcrum for such tilting movement, and a spring fitting around the stem within the base and bearing at its opposite ends against the weight and the overlying part of the base.

5. A smoking stand comprising a hollow base, a stem extending down through the base and provided with an external skirt portion resting on the base, a receptacle carried by the stem, a weight fitting slidably on the stem within the base and limited as to downward movement by the lower end of the stem, and a spring interposed between the weight and the overlying part of the base and cooperating with the weight for holding the stem in upright position.

6. A smoking stand comprising a hollow base composed of a flat-bottomed pan and a detachable cover provided with a central opening at its upper end, a tubular stem extending through said opening down into the base and terminating above the bottom and communicating with the interior of the pan, and provided with a skirt resting upon the base, a receptacle carried by and communicating with the upper end of the stem, and a weight secured on the stem within the base for normally holding the former in upright position.

30. 7. A smoking stand comprising a hollow base composed of a flat-bottomed pan and a detachable cover provided with a central opening at its upper end, a tubular stem extending through said opening down into the base and terminating above the bottom and communicating with the interior of the pan, and provided with a skirt resting upon the base, a receptacle carried by and communicating with the upper end of the stem, a weight secured on the stem within the base for normally holding the former in upright position, and a spring interposed between the weight and the upper part of the cover for cooperating with the former in holding the stem upright and in restoring it to upright position after it has been rocked or tilted.

8. In a device of the character described, a stationary hollow base to stand and maintain a vertical position on a floor, and composed of a pan and a detachable cover having a central opening, a tubular stem rising through the cover and tiltable thereon, and communicating at its lower end with the interior of the base above the bottom thereof and below the plane of the tilting point, and a receptacle on and communicating with the stem at the upper end thereof.

9. In a device of the character described, a stationary hollow base to stand on and maintain a vertical position on a floor, and composed of a pan and a detachable cover having a central opening, a tubular stem communicating with the base and provided with a skirt tiltingly standing on the cover, and means for yieldingly holding the stem against

tilting movement without impeding discharge from the stem into the base.

In testimony whereof I affix my signature.
